(57) CLAIM

We claim the ornamental design for cocktail trunk, as shown and described.

DESCRIPTION

FIG. 1 is a perspective view of a cocktail trunk according to an embodiment of the invention.

FIG. 2 is an overhead view of a cocktail trunk according to an embodiment of the invention.

FIG. 3 is a side view of a cocktail trunk according to an embodiment of the invention, the view from the opposite side being a mirror-image thereof; and,

FIG. 4 is an end view of a cocktail trunk according to an embodiment of the invention, the view from the opposite end being a mirror-image thereof.
